US00D811373S

(12) **United States Design Patent** (10) **Patent No.:** **US D811,373 S**
(45) **Date of Patent:** **** Feb. 27, 2018**

(54) **REMOTE CONTROL**

(71) Applicant: **LG ELECTRONICS INC.**, Seoul (KR)

(72) Inventors: **Junghwan Lee**, Seoul (KR); **Hyewon Kim**, Seoul (KR)

(73) Assignee: **LG Electronics Inc.**, Seoul (KR)

(**) Term: **15 Years**

(21) Appl. No.: **35/502,225**

(22) Filed: **Jul. 1, 2016**

(80) **Hague Agreement Data**

Int. Filing Date: **Jul. 1, 2016**

Int. Reg. No.: **DM/091672**

Int. Reg. Date: **Jul. 1, 2016**

Int. Reg. Pub. Date: **Jan. 6, 2017**

(30) **Foreign Application Priority Data**

Jan. 6, 2016 (KR) 30-2016-0000477

(51) **LOC (11) Cl.** **14-03**

(52) **U.S. Cl.**

USPC **D14/218**
